UNITED STATES PATENT OFFICE.

HOWARD GILMORE, OF BOSTON, MASSACHUSETTS.

ELECTRIC SWITCH.

SPECIFICATION forming part of Letters Patent No. 735,363, dated August 4, 1903.

Application filed April 18, 1902; Serial No. 103,522. (No model.)

To all whom it may concern:

Be it known that I, HOWARD GILMORE, of Boston, in the county of Suffolk and State of Massachusetts, have invented a new and useful Electric Switch, of which the following is a specification, reference being had to the accompanying drawings.

My invention relates to what are called "snap-switches," designed more especially for use in sockets for incandescent-lamps, and my invention is a switch which has a snap-make as well as a snap-break, and yet it is so inexpensive and simple in construction and so compact that it is well suited for lamp-sockets in which the room for the switch is limited and it is essential that the switches shall be supplied at low cost and be durable and not likely to get out of order.

In the drawings, Figure 1 is a plan, and Fig. 2 a section on line 2 2 of Fig. 1, showing one form of my switch and so much of a lamp-socket as is necessary to show the application of my switch. Figs. 3 and 4 are sectional views like Fig. 2, except that the switch is off in Fig. 2, half-way on in Fig. 3, and on in Fig. 4. Fig. 5 is a section on line 5 5 of Fig. 2. Fig. 6 is a section on line 6 6 of Fig. 2. Figs. 7, 8, 9, 10, and 11 are details showing the preferred construction of the key-shaft, supporting-frame, and cam for actuating the moving member of my switch. Figs. 12 and 13 illustrate a modified form of my switch in which a leaf-spring is used in lieu of the spiral spring shown in Figs. 1 to 6, and Figs. 14, 15, and 16 are details explanatory of the operation. Fig. 17 shows another modification.

The lamp-socket with the preferred form of my switch shown in Fig. 1 consists of the insulating-button A, usually of porcelain, to which is secured the frame B for the key-shaft b and also the arm d, with the binding-screw d' for the wire to one terminal of the lamp, the wire for the other terminal being connected to the frame B by arm d² and binding-screw d³, all as well known.

My switch consists of the stationary contact D and the movable contact D', which are held apart when the lamp is not lighted, but which meet with a snap when the lamp is lighted and which separate with a snap when the lamp is put out, for contact D (shown as the usual threaded shell of the lamp-socket) is in elec-

trical contact with one terminal of the filament, and the supporting-frame B, key-shaft b, cam F, and movable contact D' are in electrical contact with the other terminal of the filament, and a circuit through the filament is therefore established when contacts D and D' are in contact and maintained as long as they remain in contact, the important point 60 being to bring them into contact with a snap as well as to separate them with a snap. To effect this I actuate contact D' by means of cam F, shaped to first press contact D' toward contact D, as shown in Fig. 3, and next 65 drop one end of contact-piece D' and thereby tip that piece to the position shown in Fig. 4, thus bringing contacts D' and D together with a snap and closing the switch. The further motion of cam F carries both parts of cam F 70 clear of contact-piece D' and allows contact D' to be thrown back to its off position, as shown in Fig. 2.

I prefer to use a spiral spring b' for moving contact D' against the force of cam F, but I 75 have also shown a leaf-spring b¹⁰ for doing this. (See Figs. 12 and 13.) This leaf-spring b¹⁰ may be integral with contact D'. This feature of my invention is two contacts, the movable one of which is moved bodily by a cam 80 toward the stationary one and allowed by the cam to be moved bodily away from the stationary one by the force of a spring and is also tipped by the force of that spring on the cam as a fulcrum, so that one end of the movable contact is thrown quickly into and out of contact with the stationary contact, thereby insuring both a snap-make and a snap-break.

Another feature of my invention relates to 90 mounting the key-shaft b in its supporting-frame B, and consists in forming ears b² near the end of key-shaft b and making an aperture through the plate of frame B, as shown in Fig. 7, to receive the end of the key-shaft 95 and the ears b² when the shape shown in Fig. 7 is changed to that shown in Fig. 8, thereby securing the key-shaft b in the frame B and also centering the shaft with abundant accuracy.

A third feature of my invention relates to 100 connecting the cam F with the key-shaft, and consists in making a second set of ears b³ on the shaft b and making an aperture through

cam F, as shown in Fig. 9, so that when the shaft b and ears b³ are in place in that aperture the side walls of the aperture may be depressed into the depressions which are made by the tools in forming the ears b³, as shown in Fig. 11, and thus connect cam F and shaft b, so that the cam and shaft will always revolve together and be prevented from relative movement.

10. While I have shown the cam-surfaces as integral with a plate which revolves with the key-shaft, it is obvious that they may be integral with the contact D'. (See Fig. 17.)

What I claim as my invention is—

15. 1. The switch above described comprising two contacts, one of which is movable; and a cam and spring to move the movable contact bodily toward and away from the stationary contact, and also to tilt the movable contact over the cam as a fulcrum and snap one of its ends into and out of contact with the stationary contact, substantially as described.

20. 2. In a switch two contacts, one of which is movable; a cam to move the movable contact bodily toward the stationary contact; and a spring to oppose the movement of the mov-

able contact caused by the cam and also to tilt the movable contact over the cam as a fulcrum and thereby throw one end of the movable contact against the stationary contact with a snap when one portion of the movable contact rests on a projection on the cam, and another portion is opposite a depression in the cam.

25. 3. In a switch a supporting-frame B, one wall of which is slotted as shown with opposed curved recesses in the longer sides of the slot, in combination with key-shaft b and ears b² extending therefrom, and across the curved recesses when they engage the shaft b, substantially as and for the purpose specified.

40. 4. In a switch, a cam-plate slotted as shown with opposed recesses in the longer sides of the slot, in combination with a key-shaft provided with ears b³, extending therefrom, and filling the recesses when brought together, substantially as and for the purpose specified.

HOWARD GILMORE.
